ORESTE PENNINO, OF NEW YORK, N. Y.

DESIGN FOR A BRACELET OR SIMILAR ARTICLE.

Application filed February 6, 1928. Serial No. 25,228. Term of patent 7 years.

To all whom it may concern:

Be it known that I, ORESTE PENNINO, a citizen of the United States, residing at New York, in the county of New York and State of New York, have invented a new, original, and ornamental Design for a Bracelet or Similar Article, of which the following is a specification, reference being had to the accompanying drawing, forming part thereof.

The figure is a front perspective view of a bracelet showing my new design.

The design consists of a setting in the form of an Egyption cartouch providing a field which is ornamented with the symbolical representation of the insignia of a zodiac constellation in the center, the sign corresponding thereto at one side and the symbol of the planetary influence of the corresponding time period, at the other side.

I claim:

The ornamental design for a bracelet or similar article as shown and described.
